STEAM GENERATOR FOR FORMING AND
PRESSING DEVICES

Samuel Dowinsky, New York, N. Y.

Application June 19, 1935, Serial No. 27,446

4 Claims. (Cl. 122—4)

This invention relates to a steam generator which is designed and adapted for use in various devices for steaming, forming or shaping, and pressing fabrics, and various articles made of fabric including apparel and garments.

The principal object of the invention is the provision of a steam generator which embodies novel construction by virtue of which a unit is constituted enabling incorporation thereof in devices of the indicated character, also enabling replacement of a heating element constituting a part thereof without scrapping other parts unnecessarily, also giving an increased thermal efficiency so that steam is instantly generated and delivered upon repeatedly introducing quantities of water by suitable means connected therewith.

The nature of the invention and its distinguishing features and advantages will appear when the following specification is read in connection with the accompanying drawing, in which—

Figure 1 is a side view of a pressing and forming device selected to illustrate the invention embodied thereby;

Figure 2 is an enlarged vertical section through the device showing certain features of the invention;

Figure 3 is a section taken on the line 3, 3 of Figure 2;

Figure 4 is a section taken on the line 4, 4 of Figure 3.

Referring now more particularly to the several views of the drawing, it will be apparent that the steam generator of the present invention includes a metal body 10 of such size and shape that it may be arranged within a casing constituting a part of a device used for the various purposes mentioned. In the present instance, the body 10 is rectangular or oblong in shape. The body 10 may be made of one piece, or may be made of separate sections, as in the present instance. As shown, the body 10 consists of two sections, a section 11 and a section 12. Each section is of hollow construction to provide a space or chamber, the space or chamber in the section 11 being designated 13 and that in the section 12 being designated 14. The space or chamber in each of the sections 11 and 12 is provided by boring a hole therein from one end, the open end being closed by a removable plug 15. The section 11 has grooves 16, while the section 12 has edge portions 17 which fit into the grooves 16 respectively. Each section 11 and 12 is tapped near its upper end to receive a removable plug 18. When the sections 11 and 12 are brought to-

gether with the edge portions 17 of the section 12 in the grooves 16 in the section 11, a space 19 is formed between the sections 11 and 12 by reason of their cross sectional formations. The space 19 extends from one end of the body 10 to the other. The sections 11 and 12 are fastened or secured to each other by suitable fastening element in the form of a screw 20 which is received in tapped holes in the sections 11 and 12 which are in alinement with the plugs 18. The screw 20 has a bore 21 extending therethrough which establishes communication between the chambers 13 and 14 at a suitable distance above the bottoms thereof and thus forms one continuous passage within the body 10. The screw 20 may be employed to fasten or secure the sections 11 and 12 to each other by removing the plug 18 of the section 12. The section 11 has secured thereto a water inlet 22 which communicates with the chamber 13. The inlet 22 may be arranged at any suitable point, and in the present instance it is arranged at one side between the ends of the sections, as shown in Figure 3. The section 12 has a steam outlet 23 which communicates with the chamber 14 preferably at the lower end thereof as shown in Figure 2. A conduit conducts steam generated within the body 10 from the chamber 14 to a point of delivery. The conduit consists of a copper tube 24 which is coiled about the body 10 in contact therewith, and one end of the tube 24 is connected with the outlet 23, as at 25, and the other end 26 of the tube projects beyond the body 10. The body 10 is heated by electric heating element 27 of any suitable construction. The heating element 27 is designed to fit in the space 19 formed between the sections 11 and 12 in contact therewith so as to heat by conduction. The heating element is long enough to project beyond the opposite ends of the body 10, and is held in place with respect to the body 10 by the screw 20, the element 27 being provided with a hole for that purpose, and the resistance coil of the element having certain of the convolutions thereof widely separated to accommodate the screw 20 and avoid short circuiting. Certain convolutions of the tube 24 are also widely separated in order to afford access to the plugs 18 so that they may be removed in order to remove the screw 20, when it is desired to remove the heating element 27 should the occasion arise to replace the same. Certain refractory or ceramic or other heat resisting material 28 is applied to the body 10 with the coils of the tube 24 embedded therein.

The steam generating unit hereinabove described is designed and adapted to be arranged within a steaming, forming and pressing device. In the present instance, by way of example, the unit is arranged within the casing 29 of a device for forming and finishing scalloped edges of garments. This device includes a valve 30 secured to the casing 29 and connected with the water inlet 22 by a coupling 31. The terminals 32 of the heating element 27 are connected with binding posts 33 carried by the casing 29 and insulated therefrom. The binding posts 33 project into a receptacle or socket 34 secured to the casing 29. Electric current is supplied by conductors connected with the socket 34. A water supply pipe is connected with the valve 30, the water being obtained from any suitable source. The end 26 of the tube 24 projects upwardly through the casing 29 into a former 35 detachably secured to an extension 36 and the casing 29, by a screw 37. The former 35 is one which is adapted to shape or form a scallop on the edge of a garment or the like when inserted therein with steam being caused to issue therefrom through passages 38 opening through one face of the former 35. The heating element has a hole to accommodate the screw 37, and at this point the resistance coil of said element has certain convolutions thereof widely separated in order to accommodate the screw 37 to avoid short circuiting. The end 26 of the tube 24 loosely fits in a bore in the former 35. The casing 29 has a removable section 39 in order to incorporate the unit within the casing and to permit the removal thereof.

From the foregoing, it will be obvious that the body 10 may be heated when current is flowing to the heating element 27, and that by manipulating the valve 30 quantities of water will be introduced into the chamber 13 of the section 11. The water is admitted at intervals and is instantly converted into steam by coming in contact with the walls of the section 11. The quite moist steam flows from the chamber 13 into the chamber 14 through the passage 21, where the steam is further attenuated and enters the tube 24 through the outlet 23. The tube 24 conducts the steam to the former 35 for the stated purpose. It will thus be understood that the objects of the invention hereinbefore mentioned may be attained.

I claim:

1. A steam generator for forming and pressing devices, comprising a metal body consisting of separate sections, each of said sections being of hollow construction, means which secures said sections together and which forms a passage communicating with the interiors of said sections at a suitable distance above the bottom thereof, water inlet means communicating with the interior of one of said sections, a pipe coiled about said body in contact therewith and having one end thereof communicating with the interior of the

other of said sections and the other end of the pipe being disposed to deliver steam, said sections being formed to provide a space therebetween when secured as aforesaid, and heating means extending in said space for heating said sections.

2. A steam generator for forming and pressing devices, comprising a metal body consisting of separate sections, each of said sections being of hollow construction, means which secures said sections together and which forms a passage communicating with the interiors of said sections at a suitable distance above the bottom thereof, water inlet means communicating with the interior of one of said sections, a pipe coiled about said body and having one end thereof communicating with the interior of the other of said sections and the other end of the pipe being disposed to deliver steam, said sections being formed to provide a space therebetween when secured as aforesaid, and heating means extending in said space for heating said sections, said first means extending through said heating means to hold it in place.

3. A steam generator of the class described, comprising a metal body consisting of separate sections, each of said sections being of hollow construction, one of said sections having spaced edge portions which fit in spaced grooves in the other section to prevent lateral displacement of the sections with respect to each other, means which secures said sections together and which forms a passage communicating with the interiors of said sections at a suitable distance above the bottom thereof, water inlet means communicating with the interior of one of said sections, conduit means coiled about said body and having one end thereof communicating with the interior of the other of said sections and providing a steam outlet terminal projecting from the body, said sections being formed to provide a space therebetween when secured as aforesaid, and a heating element extending in said space in contact with the sections to heat them.

4. A steam generator comprising a metal body consisting of separate sections, each of said sections being of hollow construction, a securing element having a bore therethrough, said sections being secured together side by side by said element, said element being disposed so that its bore establishes communication between the interiors of said sections at a suitable distance above the bottoms thereof, water inlet means communicating with the interior of one of said sections, a pipe extending about said body and having one end thereof communicating with the interior of the other one of said sections and the other end of the pipe being disposed to deliver steam, said sections being formed to provide a space therebetween when secured as aforesaid, and heating means extending in said space for heating said sections.

SAMUEL DOWINSKY.
